WIRE DEREELING APPARATUS

Hugh W. Hosbein, Fort Wayne, Ind., assignor to Essex Wire Corporation, Fort Wayne, Ind., a corporation of Michigan

Filed June 10, 1963, Ser. No. 286,759

9 Claims. (Cl. 242—128)

This invention relates to a dereeling apparatus for wire and the like which is designed for easy removal of one unit of the apparatus for replacing an empty reel.

One object of the invention is to provide a dereeling apparatus in which a reel-supporting device comprises a frame on which a reel may be set with the drum of the reel in vertical position and one flange of the reel resting on the frame, a rotatable dereeling flange and a stationary flange with radially extending bristles being provided as a separable unit that may then be placed in the upper end of the reel whereupon an operative connection is effective between the dereeling flange and drive means mounted on the frame.

Another object is to provide a frame with a hub on which one end of the drum of the reel may be positioned, a drive element being rotatable within the hub and a tube being operatively connected therewith by means of cone surfaces, the upper end of the tube supporting a dereeling flange that rotates above the upper flange of the reel when supported on the frame, and means being provided extending upwardly through the tube for supporting a stationary disc above the rotating dereeling flange, the stationary disc having radially extending bristles to be successively engaged by the wire as it is dereeled and thereby keeping the wire from tangling.

Still another object is to provide the tube, the dereeling flange, the stationary disc and the bristles in the form of a removable unit permitting ready replacement of the reel when emptied and at the same time disconnection of the dereeling flange from drive means therefor so that its rotation stops upon removal of the unit.

A further object is to provide means for supporting the stationary flange and bristles in the form of an extension through the tube having disengageable means at its lower end with respect to a post extending upwardly from the frame and on which the drive element for the tube is rotatable, the construction thus being comparatively simple yet effective for support of the rotating dereeling flange as well as the stationary disc and its bristles.

Still a further object is to provide means for rotatably supporting the tube with respect to the reel comprising a plug that fits into the upper end of the reel, is carried by the removable unit and is provided with bearings in which the tube rotates.

An additional object is to provide a bearing inside the tube which rotates around the stationary extension from the post thereby insuring that all parts of the apparatus are properly journaled to eliminate vibrations, wobbling and the like.

Another additional object is to provide a dereeling device which may be used individually or in banks of several such devices whereby the inner end of the wire on one reel may be connected to the outer end of the wire on the next reel and several reels thus connected for successive dereeling of the wire from the reels without interruption in the operation of the coil winding machine using wire from the reels, empty reels being thus replaceable with filled reels in a continuous manner without interruption.

With these and other objects in view, my invention consists in the construction, arrangement and combination of the various parts of my dereeling apparatus, whereby the objects above contemplated are attained, as herein-

2

after more fully set forth, pointed out in my claims and illustrated in detail on the accompanying drawing, where in:

FIG. 1 is a plan view of a dereeling apparatus embodying my invention;

FIG. 2 is a front elevation thereof partially in section on the line 2—2 of FIG. 1 showing details of the apparatus;

FIG. 3 is a similar side elevation partly in section and on a reduced scale illustrating a dereeling flange unit being disassociated from the apparatus for removal of an empty reel and replacement thereof by a filled reel of wire;

FIG. 4 is an end view with portions broken away showing a common support for a number of my dereeling devices;

FIG. 5 is a front elevation thereof, and

FIG. 6 is a sectional view thereof on the line 6—6 of FIG. 4 showing a plurality of reels mounted thereon and showing diagrammatically the wire successive reels connected together.

On the accompanying drawings I have used the reference numerals 10 and 12 to indicate bottom and top plates which together with spacer sleeves 14 and tie bolts 16 form a frame. Casters 18, for instance of the ball type, are provided on the bottom of the plate 10 for ready transport of the frame when loaded with a reel of wire from one location to another as found desirable for dereeling wire from a reel supported on the frame. FIG. 2 illustrates such a reel, the drum thereof being indicated at 20 and the flanges thereof at 22 and 24.

A stationary post 26 extends upwardly from the bottom plate 10 and a drive element 28 is rotatable thereon, suitable bearings being provided for this purpose as shown in FIG. 2. The drive element 28 is in the form of a pulley driven from a motor 30 by means of a motor pulley 32 and a belt 34. The drive element 28 is thus rotated upon energization of the motor 30. A stationary hub 36 surrounds the drive element 28 and is secured to the top plate 12. This hub is adapted for the lower end of the reel 20—22 to be positioned thereon as illustrated with the flange 22 resting on the plate 12.

Above the flange 24 of the reel a dereeling flange 38 is provided having a depending flange 40 around the periphery of the reel flange 24. Means is provided for rotating the dereeling flange 38 and for also supporting it for rotation comprising a tube 42 having its upper end connected to the flange 38 as by means of a disc 44 and screws 46. The lower end of the tube 42 has a coupling sleeve 48 secured thereto and provided with a cone face 50 on its lower end interfitting with a complementary cone face 52 in the upper end of the drive element 28. Accordingly, when the flange 38, the tube 42 and the coupling member 48 rest by gravity on the drive element 28, they are frictionally driven therefrom through the cone faces 50 and 52.

Above the dereeling flange 38 is a stationary disc 54. Superposed on the disc 54 is a disc 56 from the peripheral edge of which bristles of nylon or the like 58 extend in radial directions as shown in FIG. 1. A handle 60 is provided for the discs 54 and 56 and means is provided for supporting these discs in a stationary manner comprising a post extension 62. The discs 54 and 56 are secured to the upper end thereof by means of a lock nut 64 and the lower end of the extension has a hex rod or the like 66 extending downwardly therefrom and its lower end removably positioned in a hex socket of a cap screw 68 secured in the upper end of the post 26.

In order to properly journal the tube 42 for rotation with respect to the reel 20—22—24 a plug 70 is provided for the upper end of the reel and has a bearing sleeve 72

in which bearings 74 and 76 for the tube 42 are provided. The tube 42 also has a bearing 78 rotatable around the extension 62 whereby the plug 70 and the bearings 74-76-78 cooperate to prevent undesirable wobble or vibration of the upper end of the tube 42 and the dereeling flange 38 which rotated thereby.

From the construction of the parts just described it will be obvious that the assembly of parts 38 through 66 and 70 through 78 may be removed as a unit (as disclosed in FIG. 3) whereby an empty reel 20-22-24 may be removed from the hub 36 and a filled reel substituted therefor. At the same time, if the drive element 28 is rotating at the time, the dereeling flange 38 will stop rotation because of being disconnected at the cone faces 50 and 52 with respect to the drive element.

Referring to FIGS. 4, 5 and 6, a common support for a plurality of the wire dereeling devices thus far described is illustrated in the form of lower and upper shelves 80 and 82 connected together by means of end frames 84 and supported on a base plate 85. The shelves 80 and 82 are inclined as illustrated in FIG. 4 and provided with stop flanges at their lower ends so that the dereeling devices may be supported thereon in rows as illustrated. A roller 86 extends across the plurality of reels as shown in FIG. 5 so that the wire 88 from a reel may extend thereover to the coil winding machine. The inner and outer ends of the wires 88 shown diagrammatically in FIG. 5 are connected together as at 90, so that as one reel is depleted the wire will automatically start dereeling from the next one and so on.

If desired, the rollers 86 may be rotated as by a motor 92 and suitable drive belts 94 and 96.

Practical Operation

In the operation of the apparatus shown in FIG. 2, when the motor 30 is energized the dereeling flange 38 is rotated in the direction that the wire 88 is dereeled from the reel 20-22-24. The rotation is preferably slightly more rapid than the wire is unreeled from the reel by the coil winding machine. As the wire passes over the depending flange 49 of the dereeling flange 38, it will drag across the bristles 58 successively and bend them as illustrated at 58a in FIG. 1, the stiffness of the bristles serving to keep the wire from becoming tangled.

When one reel has been depleted, the wire will start dereeling from the next reel and thereupon the empty reel can be removed by first lifting the dereeling flange unit from the reel as shown in FIG. 3 by means of the handle 60, and the empty reel then replaced with a filled one. When connected as in FIG. 5 the wire may be continuously withdrawn from the left-hand reel, the center reel and then the right-hand reel. The lower three reels are illustrated with the first one empty which may now be replaced with a filled one and the outer end of the wire thereon connected with the inner end of the third reel so that there is no interruption in the supply of wire from the successive reels. Only three reels are illustrated on each shelf but FIG. 5 is broken away to indicate that the rack 80-82-84 may be designed to accommodate any desirable number of wire dereeling devices.

Some changes may be made in the construction and arrangement of the parts of my dereeling apparatus without departing from the real spirit and purpose of my inven-

tion, and it is my intention to cover by my claims any modified forms of structure or use of mechanical equivalents which may reasonably be included within their scope.

I claim as my invention:

1. In a dereeling apparatus, a frame, a vertical post thereon, a drive element rotatable on said post, means for rotating said drive element, a hub on said frame surrounding said drive element and adapted to have one end of the drum of a reel positioned thereon with one flange of the reel resting on said frame, a driven tube extending upwardly from said drive element, said drive element having a driving connection with said driven tube, a dereeling flange overlying the other flange of the reel and connected with said driven tube for support and rotation thereby, a stationary disc above said dereeling flange, said post having an extension upwardly through said driven tube for supporting said stationary disc, and radially arranged bristles supported by said stationary disc and extending beyond the peripheral edge thereof to be sequentially engaged by wire dereeled from the reel.

2. A dereeling apparatus in accordance with claim 1 wherein said means for rotating said drive element rotates the same at a higher rate of speed than the tangential velocity of the wire being dereeled.

3. A dereeling apparatus in accordance with claim 1 wherein means is provided for rotatably supporting said tube relative to the reel comprising a plug in the other end of the reel drum and having bearing means in which said tube is rotatable.

4. A dereeling apparatus in accordance with claim 1 wherein said tube has a bearing therein rotatable about said extension.

5. A dereeling apparatus in accordance with claim 3 wherein said tube has a bearing therein rotatable about said extension.

6. A dereeling apparatus in accordance with claim 1 wherein said driving connection is of separable character and said extension is separable from said post whereby the assembly of tube, dereeling flange, stationary flange, bristles and extension may be removed from said frame and drive element for replacement of the reel.

7. A dereeling apparatus in accordance with claim 3 wherein said driving connection is of separable character and said extension is separable from said post whereby the assembly of tube, dereeling flange, plug and its bearing means, stationary flange, bristles and extension may be removed from said frame and drive element for replacement of the reel.

8. A dereeling apparatus in accordance with claim 1 and a common support for a plurality of said dereeling devices, said common support having a roller across all the reels for the wire from reels on said support to be successively dereeled therefrom.

9. A dereeling apparatus in accordance with claim 3 wherein means is provided for rotating said roller.
